UNITED STATES PATENT OFFICE.

HARRY S. PELL, OF AKRON, OHIO, ASSIGNOR TO THE STIRLING COMPANY,
OF CHICAGO, ILLINOIS.

WATER-TUBE BOILER.

SPECIFICATION forming part of Letters Patent No. 597,152, dated January 11, 1898.

Application filed January 12, 1897. Serial No. 618,936. (No model.)

To all whom it may concern:

Be it known that I, HARRY S. PELL, a citizen of the United States, residing at Akron, Summit county, Ohio, have invented a new and useful Improvement in Water-Tube Boilers, of which the following is a specification.

The object of my invention is to improve the Stirling type of boiler; and the invention consists in the features and combinations 10 hereinafter described and claimed.

In the accompanying drawings, Figure 1 is a vertical sectional elevation taken on line 1 of Fig. 3; Fig. 2, a transverse sectional elevation taken on line 2 of Fig. 1; Fig. 3, a plan 15 sectional elevation taken on lines 3 3 of Fig. 1; Fig. 4, an enlarged transverse sectional view of the chair, taken on line 4 of Fig. 1; and Fig. 5, a sectional elevation of the chair, taken on line 5 of Fig. 4.

20 In constructing my improved boiler I prefer to use a principal lower mud-drum A, elevated steam and water drums B, B', and B'', water-pipes b, steam-pipes b', banks of tubes C, connecting the lower mud-drums with the elevated steam and water drums, and fire-brick partitions and shelves C', all in the way generally used in a Stirling boiler; but in addition thereto I also employ various other parts or features separately or together, as 25 follows:

In order to hold the lower mud-drum steady and prevent undue strain or injury from contraction or expansion of the metal, I provide for supporting the mud-drum on what I call 30 a "spring-chair" D. The upper part of this chair d is adapted to conform to the periphery of the lower mud-drum and may be rigidly secured thereto or not, as desired. In the lower part I place a spring or springs d', just below the upper portion of the chair, in 35 position to receive any jar or shock to which the boiler may be subjected or any undue pressure caused by expansion or contraction of the metal. The spring or springs and the 40 lower part of the upper portion of the chair are preferably confined between flanges d'', extending up from the base. It will of course be understood that as many of these 45 springs may be used—one or more—as may 50 be considered practicable in any particular position or construction. This form of chair

is especially applicable when the boiler is to be used for marine purposes, in which use it is necessarily subjected to constant vibrations and jerking or surging motions.

55

The bridge-wall E in front of the lower mud-drum is preferably of hollow cast-iron construction, and the upper part of this bridge-wall is a fire-brick covering e. There is an opening e' under the bridge-wall, preferably at each side of the furnace, and the front side of the bridge-wall is perforated or provided with as many holes or openings e² as desired. Air entering through the openings under the bridge-wall passes forward through 60 the openings in its front side and thence up through the grate-bars to the furnace. In this way abundant draft is provided for, and the air which feeds the furnace also prevents the bridge-wall from warping or getting out 65 of shape or alinement.

In forming the arch F over the fireplace I prefer to use fire-bricks f of such shape as to form interlocking members. This interlocking of the members serves to hold the arch 75 together and prevents displacement and generally aids in forming a strong and durable construction. It also enables any member to be readily removed when injured by burning or otherwise, so as to permit of the ready 80 insertion of a new member without any displacement or injury to the arch.

I prefer to form the side walls G of the furnace below the arch of sections provided at their ends with suitable recesses to receive a 85 dovetail retaining member H. These dovetail members are preferably secured to or formed integral with the outer metallic wall or casing I of the boiler and serve to firmly fasten and secure the sections and wall together, hold the same in alinement, and prevent twisting or warping. They are also preferably made in such way as to leave a small air-space between the outer wall or casing and the inner sections, which air-space 90 serves to prevent undue radiation and keep the outer wall from becoming unduly heated. This form of construction enables the sections of the furnace-wall to be readily inserted or removed at pleasure without any dismantling 95 of the furnace. Where the furnace is wide, two arches may be formed with a partition in

the center to receive and support the opposing edges of the arches.

I also prefer to form the front wall L of the boiler above the arch at an incline, so as to confine the heated gases in as small a space as possible in the upper part of the boiler. As shown, this inclined wall is formed of a supporting-ledge l and fire-brick covering l'. The front wall of the furnace above the inclined portion may be supported by suitable braces or angle-irons l² or in any other convenient way. The front wall being thus inclined, a large amount of dead space is removed from the interior of the boiler, and the gases are consequently confined more closely within the front bank of tubes and loss of heat avoided.

The outer wall or casing is provided with a channel-iron I' on its inner surface in position to receive and hold the abutting ledge f' of the arch. In order to stiffen and strengthen the entire construction, I preferably place on the outer side of the metallic wall or casing angle-irons J and pass stay-rods K through the angle-irons and casing and through the furnace from side to side. These stay-rods passing through the boiler from side to side are provided with suitable washers and nuts to lock and hold them in place.

The advantages of my invention are that 30 it provides for a simple, economical, and efficient boiler, compact in form, and capable of use for either land or marine purposes.

Although I have described my invention somewhat minutely, it will of course be understood that I do not intend to limit myself to exact forms, minor features, or details of construction, or to the use of all my improvements in a single boiler. On the contrary, I contemplate making changes in form, omitting parts or using equivalents as circumstances may suggest or render expedient.

I claim—

1. In combination with the mud-drum of a water-tube boiler, a spring-chair under the mud-drum and supporting the same, substantially as described.

2. In a water-tube boiler, a furnace having its side walls formed of sections secured to the outer walls or casing by dovetail members, its arch portion formed of interlocking members, and its abutting ledges secured in channel-irons, substantially as described.

HARRY S. PELL.
